ATTORNEY

UNITED STATES PATENT OFFICE.

FREDERICK G. CORNING, OF NEW YORK, N. Y.

SAND-BOX.

SPECIFICATION forming part of Letters Patent No. 451,455, dated May 5, 1891.

Application filed February 4, 1891. Serial No. 380,217. (No model.)

To all whom it may concern:

Be it known that I, FREDERICK G. CORNING, a citizen of the United States, residing at the city, county, and State of New York, have invented certain new and useful Improvements in Sand-Boxes, of which the following is a specification.

My invention relates to means for distributing sand upon street-railways or other tracks or surfaces automatically for the purpose of promoting traction.

The invention applies either to motor-driven street-cars, motors, or to cars requiring a sanded track to render the brakes effectual.

The object of my invention is to secure a positive delivery of the sand in a measured quantity, whether in a dry condition or in a slightly-damp or partially-frozen condition, as frequently incident to its use upon street-cars; and the object is particularly to avoid interference with the operation of the movable parts by the crowding or jamming of hard substances or caked portions of the sand at the outlet. This evil is liable to occur in devices so constructed as to deliver the sand to the lower portion of the hopper, in which the delivering-surfaces converge and the movable parts travel in the direction so converging.

My invention consists in a sand-box provided with an endless chain or other flexible conveyer extending through the body of sand from one level to another, bearing buckets, disks, plates, or other irregular surfaces at suitable intervals in its length, adapted to engage frictionally with the sand, said conveyer being designed to be moved upward and convey the sand in actual opposition to gravity, passing out of the confined surface thereof, so as to catch and convey portions of it to the desired point of delivery.

My present invention constitutes a specific form of the sand apparatus generically claimed in a separate patent application filed simultaneously herewith.

Referring to the accompanying drawings, Figure 1 represents a vertical sectional elevation of the sand-box constructed in a form applicable to street-cars; Fig. 2, a vertical section of Fig. 1, taken on the line *y* *y*; and Fig. 3, a detail view showing in section a portion of Fig. 1, taken on the line *z* *z*.

In my herein-described construction of device a single side of the orbit of the chain or conveyer is passed upward through the body of sand and passed downward through a free space beneath the sand-containing box.

H represents the sand-box, constructed for convenience in the shape of a hopper, having inclined sides *h*, *h'*, and *h*². The sides *h* *h*² may be regarded as the sides proper of the box and that *h'* as the bottom, the whole being inclined at a convenient angle to the vertical to gravitate the sand upon the ascendant conveyer. The side *h*² may be dispensed with entirely; but it is illustrated as a means of increasing the vertical capacity of the box without raising the level of the free surface *a*² of the material. The box or hopper *H* is placed beneath the seats of the car, running longitudinally to the body thereof in the instance of application to street-railways, and the box may be filled from the interior of the car. A sand-box thus constructed is placed on both sides of the car above the track-wheels, a pair being employed at either end of the truck.

K is the chain or flexible conveyer, provided with buckets, disks, or other irregular surfaces *k* at intervals in its length; and *b* *b'* are sprocket-wheels for directing the chain. Power may be applied to either of the wheels *b* or *b'* for propelling the chain in a direction indicated by arrows. A suitable form of propelling device applied to the lower sprocket-wheel *b* is indicated in Fig. 2, the same consisting in a worm-wheel *b*³ and worm *b*⁴, driven by any suitable hand or power appliance—such, for instance, as that indicated in my aforesaid separate patent application. The portion of the chain within the box rests upon the bottom *h'* beneath the body of sand.

*h*² is a trough through which the chain returns and discharges the sand into the chute *J*, conducting to a point vertically above the track-rail. The chain or conveyer *K* may be made of any suitable breadth, equal or nearly so to that of the box *H*. As shown in Figs. 2 and 3, a single chain is used, and the box made narrow to accommodate it. The bottom *h'* is of concave shape in cross-section, as seen in Fig. 3, and the disks *k* given a substantially semicircular form to accommodate it. The breadth of the sprocket-wheel *b* is equal to

the breadth of the disks k and that of the box, whereby the solid portions m of the wheel between its notches n thereof that receive the disks k will close the major portion 5 of the opening a' . The remaining portion of the opening a' is closed by the disks k themselves, a curved surface a^2 being provided at the throat parallel with the orbit of the chain sufficient in length to cover at least one in- 10 terval between the disks k thereof. The out-flow of sand when the chain is at rest is thereby prevented.

The cutting or plowing edges of the disks k may be provided with upturned lips k' , as 15 indicated in Fig. 1, thus promoting the plowing action. Any small pebbles or caked portions of the sand will naturally gravitate to the lowermost portion of each pocket formed by the disks k , and thus be carried out freely 20 at a^2 through the unconfined surface of the sand. The upward motion of the part of the chain interior of the box creates a tendency to release rather than confine any hard substances that naturally settle to the bottom of 25 the mass, and the whole is constantly agitated in proportion to the force exerted by its gravity.

The conveyer K in its application herein claimed is susceptible of various constructions, corresponding to those illustrated and described with reference to the devices in my aforesaid separate patent application.

Having thus fully described my invention, what I claim, and desire to secure by Letters 35 Patent, is—

1. A sand-box provided with a movable chain or other flexible conveyer extending at an angle to the horizontal through the body of sand resting thereon and bearing at inter- 40 vals in its length a series of projections, and means, substantially as described, for operating the chain through the sand in an ascending direction.

2. A sand-box provided with a movable chain or other flexible conveyer extending at 45 an angle to the horizontal through the body of sand from a lower level thereof to and through an unconfined surface at a higher level thereof, said chain bearing at intervals 50 in its length a series of projections, and means, substantially as described, for propelling the chain through the sand in an ascending direction.

3. The combination, with a sand-box, of an endless chain or flexible conveyer having one 55 portion of its orbit included within the body of sand, occupying an angular position with reference to the horizontal, and sprocket wheels or sheaves for supporting the conveyer and propelling said included portion in an 60 ascending direction.

4. A sand-box provided with an angular bottom, upon which the body of sand chiefly or partially rests, and an endless chain or conveyer interposed thereon bearing at intervals 65 in its length a series of projections, and means, substantially as described, for propelling the chain so as to enter the body of sand at a lower level of the incline and pass out from said body at an upper level of said 70 incline.

5. The combination, with a sand-box and an angular bottom thereof, of an endless chain or conveyer having one portion of its orbit included within the body of sand parallel to 75 and resting on said bottom and another portion exterior to the body of sand, sprocket-wheels or equivalent for supporting the conveyer, and a trough vertically beneath the said exterior portion of the chain for conducting the released portions of sand to a common point of delivery.

FREDERICK G. CORNING.
